(57) **CLAIM**

The ornamental design for a hallux orthosis, as shown and described.

DESCRIPTION

FIG. 1 is a front, left side and top perspective view of a hallux orthosis, showing our new design;

FIG. 2 is a front view thereof;

FIG. 3 is a rear view thereof;

FIG. 4 is a left side view thereof; and,

FIG. 5 is a right side view thereof.

In the drawings, the broken lines depict portions of the hallux orthosis that form no part of the claimed design.
